PLASTIC BEADS

William Troutbeck Sanderson, Marlow, England, assignor to Chelton (Poppits) Limited, Marlow, England, a British company

Filed Aug. 28, 1957, Ser. No. 680,704

Claims priority, application Great Britain Sept. 20, 1956

3 Claims. (Cl. 24—217)

This invention relates to plastic beads of the kind (hereinafter described as plastic beads of the kind referred to) which are made of resilient plastic material such as polythene and in which at least one of a pair of beads is formed with a neck carrying a head and the other is formed with a socket to accommodate the head which socket is entered through a mouth of smaller cross-section than the socket interior, the head on one bead and the mouth on the other being so shaped and dimensioned in relation to one another that the bead will not ordinarily pass through the mouth but, due to the resilience of the plastic material, can be forced through with a snap action when it is desired to join two beads together, the head, neck and socket being so dimensioned that the head is smaller than the socket so as to permit of relative angular movement between the beads with free play of the head in the socket.

Heretofore it has been universal practice to make the heads of substantially spherical form and to form the mouth with a circular opening. This form of construction has been found quite satisfactory for uncoated polythene beads, but it is often required that beads should be coated for example by being metallised or pearlised. Many of these coatings have not got the elastic properties of polythene and it is found that, if a circular mouth and spherical bead are used as described above, the coating of a coated bead may split after one or more insertions of a head in the socket of a coated bead due to the distortion of the socketed bead. The effect of this distortion is that an annular ring of the coating material in the immediate neighbourhood of the socket mouth must increase in circumference in the ratio of the diameter of the bead head to that of the unstretched mouth; unless it is sufficiently elastic to do so, one or more splits occur. This splitting might be relatively unimportant if the coating could be made to adhere to the polythene but, as is well known, it is very difficult to stick anything to polythene with the result that the coating peels from the bead.

It is an object of the present invention to provide an improved form of construction for beads of the kind referred to in which the distortion of the socketed bead on insertion of the head of another bead is reduced.

According to one aspect of this invention, in plastic beads of the kind referred to, the maximum cross-sectional area of the head on one bead in a plane normal to the direction of insertion of the head in a socket is made approximately equal to the area of the mouth of a socket, the head in said plane and the mouth being shaped differently so that the head will not ordinarily pass through the mouth but, due to the resilience of the plastic material, can be forced through with a snap action when it is desired to join the two beads together.

According to another aspect of this invention, the periphery of the mouth of the socket of one bead is made greater than that of a head on another bead at the section of maximum area in a plane normal to the direction of insertion of the head in a socket, the mouth being

2

shaped differently from the head and of such size that the head will not ordinarily pass through the mouth but, due to the resilience of the plastic material, can be forced through with a snap action when it is desired to join two beads together. By this form of construction, when a head is pressed into a socket of a coated bead, an annular ring of coating material in the neighbourhood of the mouth is deformed but not increased in peripheral length and thereby the tendency to split is greatly reduced.

Most conveniently the head is of circular section in said plane and the mouth is non-circular. The head for example may be of spherical form or said head may be, outwardly from the plane of maximum cross-section, of conical form, the conical part of the head being arranged with its apex directed outwardly. For example, the head may be conico-spherical in shape, that is to say the head is formed of a hemisphere which at its diametral plane is joined to a circular cone the conical part of the head being arranged with its apex directed outwardly.

According to yet another aspect of the invention, in plastic beads of the kind referred to, the head on one bead is formed with a circular section in a plane normal to the direction of insertion of the head in a socket and the socket mouth on another bead is in the form of an aperture which is non-circular, the radial dimensions of the socket mouth being in some regions greater than and in some regions less than the radial dimensions of said circular section head so that the area of the mouth of the socket is approximately equal to the maximum cross-section area of the head in said plane.

In one form of construction the mouth of a socket is made of generally triangular form with rounded corners. A socket with such a mouth may be formed, for example, by a circular cylindrical cavity in the body of the bead with three segmental lips. Such a mouth may be formed during moulding of a bead by using a core pin of generally cylindrical form having three grooves, e.g. milled cuts around its surface end to end to form the three segmental lips in the moulding, the grooves being of such length that their ends do not quite meet so that there are short arcuate portions of the cavity wall between the lips.

In order to minimise the size of the neck on plastic beads, which is particularly desirable to enable the appearance of small beads to be improved, the ratio between the pressure necessary to join the beads and the force necessary to pull the beads apart should be as low as possible. To this end, conical ended heads may be used as described above and preferably also the lips on the mouth of the sockets are shaped so as to have an outer face which slopes from the socket wall inwardly towards the interior of the socket so as to facilitate the sliding in of a head. Preferably also the lips have an inner face which preferably extends at right angles to the axis of the socket so as to offer the maximum resistance to the withdrawal of a head.

The invention also includes within its scope a plastic bead of the kind referred to and having a head and a socket with a mouth, the head in the plane of maximum cross-sectional area normal to the direction of insertion in a socket of another bead being shaped differently in cross-section from the mouth of the socket.

In the following description, reference will be made to the accompanying drawings, in which—

Figure 1 is a cross-sectional view of a bead,

Figure 2 is an end view of the bead of Figure 1 looking in the direction of the arrow A,

Figure 3 is an end view of the bead of Figure 1 looking in the direction of the arrow B,

Figure 4 is a view in elevation of part of a core pin for use in moulding the bead of Figures 1 to 3, and

Figure 5 is a section along the line 5—5 of Figure 4.

Referring to Figures 1 to 3 there is illustrated a bead formed of polythene and having a generally spherical body 10. Protruding from this body is a neck 11 having a head 12, this head being formed at its outer end in the shape of a frustum of a cone 13 with the apex of the cone directed outwardly. The head is joined to the neck by a very short section 14 which is also of generally conical form with an obtuse apex angle such that this surface is almost at right angles to the axis of the neck and head.

The body 10 contains a cavity 15 with a mouth 16 formed by the inwardly-directed lips 17. These lips are each formed as a web across the mouth of the cavity 15, so that the mouth entrance is of generally triangular form with rounded corners as most clearly seen in Figure 2. The mouth 16 is made of such size that the cross-section area of the mouth at the lips is approximately equal to the maximum cross-sectional area of the head 12 in a direction perpendicular to the axis of the neck and head. It will be seen that the head of one bead can be inserted through the mouth into a socket of a similar bead with a snap action in a manner similar to that described in specification of British Patent No. 750,737. By forming the mouth of triangular form as described above with its cross-sectional area approximately equal to that of the head, very little distortion of the body of a bead occurs when the head of another bead is inserted or withdrawn from the socket of the first bead. This arrangement has particular advantage if the body of the bead is coated with a pearl or other hard finish. Most pearly and metallising finishes for plastic beads tend to split or peel off if the bead is distorted and the arrangement of the present invention thus minimises the possibility of the coating peeling.

The particular form of head described above enables the head to be inserted easily into the socket since the conical surface 13 of the head, as it is inserted in the mouth, gradually distorts the lips of the mouth. Greater force, however, is necessary to pull the beads apart than to join them together since the inner face of the lips 17, as shown in Figure 1, are arranged to extend at right angles to the axis of the socket and thus to engage on the rear face 14 of the head when the beads are pulled apart.

The form of bead illustrated in Figures 1 to 3 is most conveniently made by moulding and the socket shown in Figures 1 and 2 may be made whilst the bead is being moulded by using a core pin 20 as shown in Figures 4 and 5. It will be seen that the core pin has three grooves

21, which may conveniently be formed by milling, these grooves being shaped so as to form the required lips 17 on the mouth 16 of the socket. It will be seen that the grooves 21 are of such length that their ends do not quite meet so that there are short arcuate portions of the cavity wall between the lips.

I claim:

1. In a multiple bead assembly formed by identical beads, a bead of resilient plastic material of the type which may be snapped one into the other comprising a body portion of which a part thereof has an integral neck with a head thereon wider than said neck, an opposite part of the body portion having a cavity extending thereto with a mouth portion which is triangular in cross section, said mouth being formed by spaced segmental lips which define shoulders inside the cavity, said lips being inwardly inclined, the shoulders of said mouth portion being adapted to engage the head portion of an adjacent bead to hold the beads together, and said head portion being frusto-conical in longitudinal cross section so that when two adjacent beads are inter-engaged, the frusto-conical head is received in the cavity and is held by the shoulders defined by the segmental lips inside the cavity, and the insertion of the head in the cavity taking place with distortion of the lips with no substantial distortion of the body portion beyond the lips.

2. A bead according to claim 1, in which the internal shoulder of each lip is at right angles to the longitudinal axis of the bead.

3. A bead according to claim 1, in which the mouth portion has a cross sectional area at the lips approximately equal to the maximum cross sectional area of the head in a direction perpendicular to the longitudinal axis of the bead.
